TRUE-BITE ATTACHMENT

George J. Keller, Detroit, Mich.

Application April 10, 1933, Serial No. 665,276

3 Claims. (Cl. 32—19)

This invention relates to a true-bite attachment.

In the fabrication of artificial dentures, after the bite blocks have been formed in any of the well-known ways, the problem arises of properly fitting the teeth into the bite blocks so that the artificial dentures will function efficiently. It is imperative in the setting of the teeth in the bite blocks that the normal relative movement of the patient's jaws be taken fully into account. If the movement of the lower jaw relative to the upper jaw is not properly recorded and thoroughly taken into account it will inevitably follow that the teeth of one bite block will not be properly set relative to the teeth in the other, and consequently abnormal pressures will be thrown upon the patient's jaw muscles causing unnecessary fatigue and discomfort. Further, free, normal relative movement between the teeth of the upper and lower bite blocks will not be attained with the result that the artificial dentures, and particularly the lower denture, will move or tilt from its normal proper position. This displacement from the normal of the upper and lower artificial dentures is due to improper condyle path depth which prevents free and normal jaw movement imperceptible to the patient.

As is well known in the art, after the bite blocks have been molded or formed to properly conform to the roof and gums of the upper and lower jaws of the patient, these bite blocks are placed in an articulator which essentially is a mechanical set of jaws properly adjustable to simulate the normal movement of the lower jaw relative to the upper jaw of the patient. Obviously the movement of the lower jaw of each patient relative to his upper jaw is different from that of any other patient. Consequently it is very essential that a proper apparatus be utilized to record the individual jaw movements of the patient and thereby effect an adjustment of the articulator so that the articulator in turn will produce a relative movement between the upper and lower bite blocks which is an exact reproduction of the jaw movements of the patient. This is the object of the present invention, namely, to produce a true-bite attachment which will effectively and accurately record the centric, protrusive, and lateral movements of the lower jaw relative to the upper and effectuate the adjustment of the articulator so that the operation of the articulator will effect the accurate normal jaw movements of the patient between the upper and lower bite blocks to facilitate the proper setting of the teeth in the bite blocks.

In the drawing:

Fig. 1 is a vertical longitudinal section of the attachment.

Fig. 2 is a top plan view of the attachment showing the attachment in the centric bite position in the full lines and in the protrusive bite position in the dotted lines.

Fig. 3 is a top plan view showing the position of the attachment in the right lateral bite position in the full lines and in the left lateral bite position in the dotted lines.

Fig. 4 is a bottom plan view.

Referring more particularly to the drawing it will be seen that the attachment comprises an upper flat plate 1 and a lower flat plate 2 which are arranged for relative sliding and swiveling movement. To this end the upper plate is provided with a longitudinal slot 3 and the lower plate is provided with an arcuate slot 4 for reception of the bolt 5. The bolt 5 projects through and slidably engages the upper plate 1 in the longitudinal slot 3 and the lower plate in slot 4 and is provided with a wing nut 6. Hence, when the wing nut 6 is drawn tight the two plates 1 and 2 are tied immovably together. When the wing nut 6 is loosened the lower plate 2 can move longitudinally back and forth along the upper plate 1 owing to the longitudinal slot 3 and likewise is free to move laterally owing to arcuate slot 4.

The upper and lower plates 1 and 2 are provided with detachable upper and lower bite rims 7 and 8 respectively. The bite rims 7 and 8 are each provided on their upper and lower faces respectively with a pair of projecting prongs 9 which engage in the sockets 10 mounted at the ends of the upper and lower plates. The prongs can be held tightly in the sockets 10 by means of the set screws 11. The bite rim 7 has secured thereto the upper bite block 12 and the lower bite rim 8 has secured thereto the lower bite block 13. The bite blocks 12 and 13 are made of wax or any other suitable substance in the well-known manner. The upper and lower bite rims have secured to their top and bottom faces respectively a pair of dowel pins 14 for securing the bite blocks to the bite rims and for preventing any relative movement between the bite blocks and the rims. The dowel pins 14 likewise serve as markers in the assembly of the bite rims to the bite blocks, that is, in the assembly of the bite blocks to the bite rims the bite blocks are inserted in the proper position in the mouth, then the bite rims are placed in the mouth between the bite blocks and the bite blocks closed

down upon the rims which causes the dowel pins 14 to leave marks upon the bite blocks whereupon the bite rims can be removed, followed by the removal of the bite blocks and the marks left by 5 the dowel pins availed of in properly positioning the bite blocks upon the rims when sealing and securing the blocks to the rims.

The upper plate 1 is provided with the upwardly bent lugs 19 and 20 which support the 10 guide sleeves 21 and 22 respectively for the recording pins 23 and 24. Suitable spring members 25 and 26 which are tensioned and exert a downward thrust upon the recording pins 23 and 24 are secured to plate 1 by the screws 17 and 18. The pin guide sleeves 21 and 22, and necessarily the pins 23 and 24 are placed in tandem relation and preferably in exact longitudinal alignment along the central longitudinal axis of the upper plate 1. The lower plate 2 15 projects beyond both ends of the upper plate 1 so that the recording pins 23 and 24 yieldably engage the upper face of the lower plate as at 30 and 40. It will be noted that the recording pin 23 is positioned outwardly from the patient's 20 mouth a sufficient distance to be within the normal sight range of the patient. The normal sight range as herein used may be defined as that area in which the patient can easily and normally, without straining or cocking his eyes, see 25 the recording pin effect its graphic recording of his jaw movements upon the surface of the lower plate.

If a practically successful and accurate graphic recording of the several bites of the patient's 30 jaws is to be obtained then it is essential that no unnatural pressure be placed upon the jaws of the patient. To this end the pins 23 and 24 are positioned in tandem relation and preferably, 35 although not necessarily, along the central longitudinal axis of the upper plate. Hence, when the lower plate is moved by the patient to graphically record the right and left lateral bites, and if the plates 1 and 2 should tilt one relative to the other, the pin springs 25 and 26 will not be 40 placed under tension additional to that necessary for proper recording because they are in tandem relation and consequently no unnatural pressure is placed on the patient's jaws and in particular the jaw muscles on the one side of the 45 face are not placed under a greater unnatural pressure than the jaw muscles on the other side of the face.

The operation of the attachment is as follows:

After the bite blocks are made in any of the 50 well known ways they are then inserted in the patient's mouth. The bite rims which are attached to plates 1 and 2 are then placed between the bite blocks. The patient is now instructed to close his mouth so that the dowel pins 14 on the 55 bite rims will impale the bite blocks. This is done to position the attachment in parallel relation with an imaginary line drawn from the auditory meatus to the wing of the patient's nose. The plates 1 and 2 are now detached from the bite 60 rims and the bite rims and attached bite blocks removed from the mouth. The bite rims are secured to the bite blocks preferably by hot sealing wax which is subsequently thoroughly chilled. The bite rims are flat plates and the lower face 65 of the upper plate has a flat surface engagement with the upper face of the lower plate 8. The bite blocks 12 and 13 with the bite rims 7 and 8 attached are now placed in the patient's mouth. The upper bite block 12 is in engagement with the 70 roof and the lower bite block 13 in engagement 75

with the bottom of the patient's mouth. After the bite blocks have been placed in the patient's mouth the plates 1 and 2 are now secured to the bite rims 7 and 8 by passing the sockets 10 over the projecting prongs 9 until the adjacent edges 5 31 and 32 of the plate 2 and the bite rim 8 respectively are brought into flush engagement as shown in Figure 1 and until the edge 41 of bite rim 7 abuts the sockets 10, Figure 2. At this time the friction screws 11 are turned down to tightly 10 secure the prongs 9 in the sockets 10.

The lower plate 2, which, of course, moves with the lower jaw of the patient, is first provided on its upper face in the area surrounding the points of contact of the pins 23 and 24 with the upper face of the plate 2 with a suitable recording surface of colored wax or a mixture of lamp-black and paraffin 42. Inasmuch as the pin 23 is within the normal range of the patient's vision and clearly visible to him, the patient is aided materially in making his centric protrusive and right and left lateral movements because he can watch the pin as it graphically records these movements. The psychological state of the patient while in the dentist's chair must be remembered. The patient is usually nervous and anxious for fear the next move of the dentist will hurt him. If the patient can see the instrument and watch it graphically record his jaw movements, he will be relieved from his anxiety knowing full well that there will be no pain involved and consequently his jaw muscles will be relaxed and the movements of his jaw normal. At this time the patient extends his lower jaw forwardly as far as possible 20 whereupon the lower plate 2 slides longitudinally and forwardly along the upper plate 1 to the position shown in the dotted lines of Figure 2. It will be noted that the bite rims 7 and 8 are flat plates and when in the patient's mouth have a flat surface engagement, thus there is no chance for the 30 bite rims 7 and 8 to tilt one relative to the other and consequently the pressure on the jaw muscles at all points is normal. As the lower plate moves forwardly along the upper plate, the wing nut 6 having first been loosened, the pins 23 and 24 35 graphically record in the wax recording surface a longitudinal line 43 indicative of the centric and protrusive bites of the patient. After the patient draws his lower jaw back to the normal or centric position, he then moves his lower jaw consecutively to the right and left lateral bite positions. At this time the upper plate 1, as shown in 40 Figure 3, obviously remains stationary whereas the lower plate 2 swings to the right lateral bite position shown in the full lines and to the left lateral position shown in the dotted lines. At the same time the recording pins 23 and 24 45 graphically record on the wax recording surface a V line 44 indicative of the right and left lateral positions of the patient's jaw. The patient now returns the jaw to the normal position whereupon the wing nut 6 is screwed tightly down thus securing the plates 1 and 2 tightly together in the normal position of the patient's jaw. At this time the friction screws 11 can be loosened and the 50 plates 1 and 2 detached from the bite rims 7 and 8. The bite rims with the bite blocks attached are now removed from the patient's mouth. Models of the patient's mouth are now securely fastened to the bite blocks. The rims, with the bite blocks 55 and models attached, are again securely attached to plates 1 and 2. The bite rims are then pressed firmly together and sealed with hot sticky wax or the like which in turn is chilled to securely bind the two rims together. The bite blocks are 60

now paralleled and positioned in the articulator preferably utilizing the spirit level attachment shown in my copending application Serial No. 637,154, so that they assume the same relative 5 angular position as they assumed in the patient's mouth.

At this time the bite blocks and attachment are then secured in the articulator in any of the well-known ways, such as by casting them in position with a suitable plastic composition such as 10 plaster of Paris with a suitable accelerator. As soon as the casting material has hardened the wing nut 6 is loosened and the articulator being mounted in centric relation may be adjusted for 15 the right and left lateral bites by retracting the graphic recording lines which have been traced upon the wax recording surfaces by the pins 23 and 24. At this time the axial alignment of the pins 23 and 24 proves very useful because when 20 the pins 23 and 24 are placed in the centric bite position the upper and lower mechanical jaws of the articulator are automatically aligned which eliminates any guess work or trial and error method in the alignment of the mechanical jaws. 25 After the articulator has been properly adjusted for the centric and right and left lateral bites of the patient by retracing the recording upon the lower plate, plates 1 and 2 are removed from the bite rims 1 and 8, the bite blocks 12 and 13 are 30 then removed from the models. The models of the roof and upper gums and the bottom and lower gums of the patient's mouth now remain in the articulator and are free to move with the articulator, one relative to the other substantially and in exactly the same manner as the actual 35 lower jaw of the patient moves relative to his upper jaw. The setting of the teeth on the models will now be effected.

I claim:

1. A true-bite attachment comprising in combination upper and lower bite blocks, upper and lower plates secured respectively to said upper and lower bite blocks, the said plates being slidably connected by a pin and slot connection for relative longitudinal and lateral movement, a pair of yieldable pins mounted upon one of said plates in spaced relation along the longitudinal axis of one of said plates and in contact with the other of said plates for graphically recording relative longitudinal and lateral movements between the said plates. 10

2. A true-bite attachment comprising in combination upper and lower flat plates adapted to be secured respectively to upper and lower bite blocks, the lower surface of the upper plate being in flush engagement with the upper face of the lower plate and laterally and longitudinally slidably connected thereto, a connection between the plates in the form of a pin and slot and a pair of 15 yieldable recording pins spaced longitudinally centrally of one of said plates and yieldably engaging the other of said plates for graphically recording the relative longitudinal and lateral movements between the said plates. 20

3. A true-bite attachment comprising in combination upper and lower bite plates adapted to be secured to upper and lower bite blocks, one of said plates having a longitudinal slot and the other plate having a lateral arcuate slot, means 25 passing through the said slots for movably connecting the two plates together, and a pair of yieldable recording pins spaced in tandem relation longitudinally of one of the said plates and yieldably engaging the other of said plates for 30 graphically recording relative longitudinal and lateral movements between the said plates. 35

GEORGE J. KELLER.
